UNITED STATES PATENT OFFICE

119,415

DESIGN FOR A WIND DEFLECTOR

Frank S. Wheeler, Los Angeles, Calif.

Application October 25, 1939, Serial No. 87,864

Term of patent 7 years

To all whom it may concern:

Be it known that I, Frank S. Wheeler, a citizen of the United States, residing at 449 N. Rockingham Avenue, city of Los Angeles, county of Los Angeles, and State of California, have invented a new, original, and ornamental Design for a Wind Deflector, of which the following is a specification, reference being had to the accompanying drawing, forming part thereof.

Fig. 1 is a plan view of a wind deflector showing my new design. Fig. 2 is an end view of the wind deflector of Fig. 1.

I claim:

The ornamental design for a wind deflector, substantially as shown.

FRANK S. WHEELER.
